SUCTION NOZZLE

Gustaf Einar Lofgren, Riverside, Conn., assignor
to Electrolux Corporation, Dover, Del., a corpora-
tion of Delaware

Application April 2, 1938, Serial No. 199,571

3 Claims. (CL 15—157)

My invention relates to suction nozzles and more particularly to suction nozzles having a plurality of suction openings.

An object of my invention is to provide an improved suction nozzle with one suction opening for efficiently removing embedded dirt and another suction opening which may be used either for removing loose surface material or lint, threads, hairs, and the like, adhering to the surface of the rug.

Another object of my invention is to provide a suction nozzle with three cleaning positions, any one of which may be readily presented for cleaning a particular material or for removing dirt of any particular character.

A further object of my invention is to provide an improved suction nozzle with means for readily and efficiently removing surface lint, hairs, threads, and the like.

What I consider to be novel and my invention may be better understood by reference to the following specification and appended claims when considered in connection with the accompanying drawings, in which—

Fig. 1 is a top view of my improved nozzle;

Fig. 2 is a side view partly in section;

Fig. 3 is a top view with the comb sleeve in a different position from that of Fig. 1;

Fig. 4 is an enlarged sectional view of a portion of the suction nozzle;

Fig. 5 is a detailed view of a portion of the suction nozzle;

Fig. 6 is a sectional view similar to a portion of Fig. 4 showing the sleeve in a different position;

Fig. 7 is a sectional view taken at right angles to Fig. 4; and

Fig. 8 is a side sectional view showing the suction nozzle in a different position from that of Fig. 7.

Referring to the drawings, 10 indicates a suction nozzle generally having a body 11 with an enlarged suction opening 12 on one side and a smaller opening 13 at the other side. Opening 12 is bounded by a smooth lip 14 having an arched cross-section, as best shown in Fig. 7, with a rearwardly extending flange 15 located at each end of the body 11. The top opening 13 is considerably smaller than the opening 12. A plate 16 covers the opening 13 and has a central passage 17 communicating with the opening 13. Located at one side of the passage 17 is a rod 18 with alternate transverse tongues 19 and grooves 20. Rod 18 is provided with extensions 21 at each end which enter openings in L-shaped plates 22. A substantially cylindrical sleeve 23 having an open-

ing 24 at one side is positioned over the rod 18. When sleeve 23 is in the position indicated in Fig. 1, the tongues 19 and grooves 20 are uncovered. A finger grip 25 is formed integrally with the sleeve 23 and may be utilized for turning the sleeve over to cover the tongues 19 and grooves 20 of rod 18 as shown in Fig. 3. Plate 16 is provided with tongues 26 and grooves 27 adjacent the edge of passage 17 on the side opposite to rod 18. As best indicated in Fig. 7, the top of tongues 26 are in substantially the same plane as the top surface of plate 16 at the opposite side of passage 17. At opposite ends of the plate 16, surfaces 28 are provided and extend slightly above the top of rod 18. When sleeve 23 is in the open position indicated in Fig. 4, a spring 29 engages in a slot 30 provided in one end of the sleeve 23. When sleeve 23 is moved to the closed position as indicated in Figs. 6 and 7, the spring 29 engages the free edges adjacent the opening 24 of sleeve 23. Spring 29 is substantially of U-shape with the end 31 positioned at right angles to the axis of sleeve 23. The opposite end of spring 29 is connected to one of the plates 22 by means of hollow rivets 32 as indicated in Figs. 5 and 6. The plate 16 together with the rod 18, sleeve 23, and spring 29 are secured to body 11 by means of two bolts 33. Lock washers 34 are provided on bolts 33. A tube 35 is pivotally secured in an opening 36 midway between the two ends of body 11 by means of a plate 37 and bolts 38. An annular ring 39 is secured to tube 35 by means of peening as indicated at 40 in Fig. 8. Ring 39 is provided with an outwardly extending flange 41 which rests in an annular recess 42 provided adjacent to opening 36. The end of tube 35 is spaced from wall 43. An opening 44 is provided in tube 35 at one side which may be registered with the suction opening 12 in one position as indicated in Fig. 2, or with the opening 13 when located in the position indicated in Fig. 8. A transverse wall 45 provided within body 11 divides it into a top chamber 46 communicating with opening 13 and a bottom chamber 47 communicating with opening 12. When tube 35 is in the position indicated in Fig. 2, the opening 44 is in communication with the chamber 46 through an opening 48 provided in transverse wall 45. When tube 35 is in the position indicated in Fig. 8, opening 44 of tube 35 is in communication with chamber 46 through an opening 49 in transverse wall 45. To provide a smooth path for flow of air from the ends of suction opening 12 to opening 48 of transverse wall 45, two plates 50 are provided and secured to posts 51 of body 11 by means of screws

52. To facilitate the selection of suction opening 12 or suction opening 13, a weight 53 is located in one end of the body 11 to unbalance the body 11 to rotation about tube 35.

In cleaning a rug, a vacuum cleaner is connected to suction nozzle 10 by means of a flexible hose or conduit connected to tube 35. For the general cleaning of a rug, the nozzle is moved back and forth over the rug with the suction opening 12 in contact with the rug. As the nozzle 10 is moved over the rug, the suction of the vacuum cleaner produces a large flow of air through the opening 12 which readily removes the embedded dirt from the rug. In some cases it may be desired to use the suction nozzle 10 simply to remove surface dirt from a part of the rug without cleaning the whole rug. This may be accomplished most efficiently by reversing the position of body 11 with the suction opening 13 in contact with the rug surface. For simply removing loose surface dirt, the tongues and grooves of rod 18 may be covered by the sleeve 23. However, if the surface dirt consists of lint, hairs, threads, and the like which adhere to the surface of the rug, it may be more efficiently removed by rotating the sleeve 23 to the position to uncover the tongues 19 and grooves 20 of rod 18. The tongues 19 and grooves 20 or rod 18 loosen the lint, threads, and the like and permit the flow of air at a relatively high velocity due to the small suction opening 13 to carry the lint, etc. into the vacuum cleaner. When the suction opening 13 is used for removing surface dirt, the smaller suction opening provides a higher velocity of air flowing through the nozzle 10 increasing the lifting force for light material. The tongues 26 and grooves 27 in the plate 16 insure a flow of air along the surface of the rug even when the sleeve 23 is in the closed position and the suction holds the rug in close contact with the plate 16. Even with a high suction it is difficult to remove surface litter without a flow of air along the surface being cleaned. The end surfaces 28 formed integrally with plate 16 are positioned above or beyond the top of rod 18 and the portion of plate 16 adjacent the sides of passage 17. This provides a further insurance of a flow of air along the surface of the rug and so prevents the rug from sealing tightly against the passage 17.

By the provision of a relatively large suction opening 12 and a smaller suction opening 13 with the rod 18 and sleeve 23, a triple action suction nozzle is provided for removing quickly

with a minimum of effort any of the three general types of dirt found in the rug, namely, embedded dirt in the nap of the rug, loose surface dirt, and threads, hairs, and the like which adhere to the rug surface.

What I claim is:

1. A suction nozzle comprising a body member having an elongated suction opening, spaced projections extending outwardly from said body member along one side of said opening, a rod having transverse tongues and grooves secured adjacent the other side of said suction opening and extending outwardly from said body beyond the projections at the opposite side of said opening, a sleeve extending over said rod and serving to cover and uncover said tongues and grooves in alternate positions, and extensions from said body at each end of said opening extending outwardly beyond said tongues.

2. A suction nozzle comprising a body member having an elongated suction opening, spaced projections extending outwardly from said body along one side of said opening, a rod having transverse tongues and grooves secured to said body at the other side of said opening, said tongues extending outwardly beyond the projections at the opposite side of said opening, a sleeve extending over said rod adapted to cover and uncover said tongues and grooves in alternate positions, a spring secured to said body and engaging said sleeve to hold the sleeve in its alternate positions, means to rotate said sleeve from one position to another, and extensions at each end of said opening extending outwardly beyond said rod.

3. A suction nozzle comprising a body member having an elongated suction opening, spaced projections extending outwardly from said body along one side of said opening, a rod having transverse tongues and grooves secured to said body at the other side of said opening, said tongues extending outwardly beyond the projections at the opposite side of said opening, a sleeve rotatably mounted on said rod and having an elongated slot, means to rotate said sleeve so as to cover and uncover said tongues and grooves in alternate positions, said sleeve being formed at one end with a recess diametrically opposed to said slot, a spring secured to said body and engageable with said slot and said recess for retaining said sleeve in its alternate positions, and extensions at each end of said opening extending outwardly beyond said rod.

GUSTAF EINAR LOFGREN.
